UNITED STATES PATENT OFFICE.

FREDERIC C. CHADBORN, OF NEWBURGH, NEW YORK.

BURNER.

1,079,327.

Specification of Letters Patent. Patented Nov. 25, 1913.

Application filed November 30, 1912. Serial No. 734,260.

To all whom it may concern:

Be it known that I, FREDERIC C. CHADBORN, citizen of the United States of America, residing at 221 Third street, Newburgh, in the county of Orange, State of New York, have invented certain new and useful Improvements in Burners, of which the following is a specification.

My invention relates to improvements in burners for gaseous fuels.

The primary object of the invention is to provide an improved form of burner whereby in a mixture consisting of gas and a preponderating amount of air will burn with an intensely hot flame.

A further object of the invention is to simplify and improve the structure of a burner of this type whereby the cost of producing the same and the facility with which the burner may be constructed, will be minimized.

A further object is to provide a type of burner which is adapted to sustain a flame of extremely high temperature in a space in which atmospheric air or oxygen does not easily circulate, such for example as the dead air space below a boiler.

Other objects and advantages of the invention and its detail structure and operation will be more fully hereinafter described, reference being had to the accompanying drawing, wherein—

Figure 1 is a vertical longitudinal section of the preferred form of burner, certain parts being shown in elevation; Fig. 2 is an elevational view partly in section of a modified form of burner; and Fig. 3 is a similar view of a modified form of disk more fully hereinafter referred to.

My improved form of burner is especially designed to be used as a water heater and is adapted to be placed under boilers for the purpose of quickly and economically heating the water therein. I desire it to be understood however, that the application of the invention is not limited to this use and that the burner may be employed practically in any connection where an intensely hot flame is required.

I have found in practice that the more thoroughly the air and gas are admixed, and the better the preheating of such mixture,

prior to its ignition, the more intensely hot will the flame be.

Having in mind the facts set out in the paragraph immediately preceding, I provide in the structure of my burner, a suitable casing designated generally as 10, the lower portion of which is provided with air admission openings 11 of considerable area. The casing 10 is supported by a standard or pedestal 12 into the base 13 of which the fuel supply pipe 14 opens. 15 is the gas nozzle.

All that portion of the interior casing above the air and gas admission openings 11 and 15 respectively, may be considered to be the mixing chamber and has been designated generally by the numeral 16.

The air and gas naturally commingle upon entering the mixing chamber 16, but to provide for a further admixture of the entering air and gas, I may employ a mixing device which consists of a series of wings 17, the outer edge of each presenting an ogee curve and the lower edge portion of each wing being threaded at 17^a to engage threads 10^a formed at approximately the median part of the inner wall of the casing 10. The extreme lower edges 17^b of the mixing device are practically knife edges so as to minimize the possibility of their acting as baffles or retarders to the upward flow of the gaseous mixture. The upper part 10^b of the casing is preferably of substantially globular formation, and the wings 17 at this globular portion are correspondingly enlarged as to diameter. The air and gas mixture at this point is permitted to expand considerably owing to the globular formation of the part 10^b of the casing.

Suitably attached to, or formed integrally with the upper edge of the globular part 10^b of the casing is a sleeve like extension 18 which becomes highly heated when the air and gas mixture is ignited, the heat from the extension 18 being conducted down through the casing 10. The walls of this extension are preferably somewhat inclined for a purpose to be described, the extension 10^b to a certain extent forming a truncated cone.

Resting upon the upper ends or edges of the mixing device 17 is a suitably shaped disk 19 which serves to spread the flames

and cause them to impinge upon the inner wall of the extension 18, and which disk in combination with the extension 18 and the mixer 17 also assists in heating the mixture 5 of gas and air to be ignited.

The operation of the form of invention above described is as follows: Assuming the gas from a source not shown to be flowing through the pipe 14 and out at the nozzle 15, 10 air in considerable quantities will be drawn in through the openings 11. The air and gas will commingle in the lower part of the casing 10 and as this mixture rises in the mixing chamber 16 it will flow against the 15 staggered wings 17 where it will be subjected to further mixing and agitation. Assuming now that a flame be applied at the opening 20 between the inner edge of the extension 18 and the periphery of the disk 19, the gas 20 and air mixture will be ignited and will burn as a flame of substantially round or annular shape. The flame will act against practically all parts of the inner surface of the extension 18 and this heat will be conducted down through the casing 10 and the 25 radiation from the casing 10 will be sufficiently intense to heat to a very high degree the air and gas mixture almost at the moment of its entrance into the mixing chamber 16. The flame will also have a tendency 30 to heat to a very substantial degree the disk 19 and the mixer 17 so that the latter will also assist in heating the air and gas mixture in its upward passage through the mixing 35 chamber.

In the modified form of the invention, the construction and operation are substantially analogous to those of the preferred form. 10 is the burner casing, 11 the air admission orifices, 12 the pedestal, 13 the base, 14 the gas admission pipe, 15 the gas admission nipple, 17 the mixer, and 18^a is a slightly modified form of extension which is provided with a plurality of holes near its lower 45 edge, each of which holes is adapted to receive one end of a pipe or tube 21, the lower end 21^a of which is open to atmosphere, these several pipes being designed to supply air to the combustion space in addition to that 50 drawn in through the air admission openings 11. In other respects the modified form of invention is analogous to the preferred form and no further description of such modified form is thought to be required.

55 In Fig. 3 I have shown a modified form of disk or flame spreader, 19^a being the disk proper and having projecting from its upper face a series of pins or what may be termed heat conductors 22. These pins are spaced 60 apart so as to withdraw from the flame a greater or less amount of heat which is transmitted to the wings 17 and by them conducted down into the space which forms the mixing chamber. In the forms shown

in Figs. 1 and 2, the disk 19 is substantially 65 of a sharp conical formation and acts practically in the same manner as does the modified form illustrated in Fig. 3.

I have found in practice that a burner of the type herein described may be placed 70 under a boiler, the space being practically dead so far as the circulation of oxygen is concerned, and an intensely hot flame will be sustained in the burner as long as the supply of fuel is continued. This result is 75 no doubt in part due to the fact that by the intense heating action of the several parts which participate in this function, the entering air and gas mixture is highly agitated and heated, and also due in part to the fact 80 that by providing air admission openings considerably greater in area than the fuel admission opening, a sufficient quantity of oxygen is carried up to the point of ignition to sustain the flame and to keep a constant 85 very strong draft in motion.

I claim:

1. A burner for gaseous fuel embodying therein a casing, an extension projecting from one end of said casing to form means 90 for conducting heat to the walls of the casing, a mixing device having a series of ogee-shaped wings depending within the casing, and means supported by said mixing device for spreading the issuing flame whereby the 95 same is caused to impinge against the inner wall of said extension.

2. A burner for gaseous fuel embodying therein a casing, an extension projecting from one end of said casing to form means 100 for conducting heat to the wall of the casing, a combined heater and mixer within said casing consisting of a plurality of substantially ogee-shaped wings, and a disk supported by said combined mixer and heater 105 and adapted to spread the flames whereby the latter are caused to impinge against the inner wall of said extension.

3. A burner for gaseous fuel embodying therein a casing having the inner face of its 110 wall at substantially its median portion screw threaded, an extension projecting from one end of said casing, a combined heater and mixer consisting of a plurality of substantially ogee-shaped wings having portions thereof threaded to engage the threads on the wall of said casing, and a disk supported by said wings and adapted to spread the issuing flame and cause the same to 115 impinge against the inner wall of the said extension.

4. A burner for gaseous fuel embodying therein a casing, an extension projecting from one end of said casing, and being provided with a series of orifices, a series of substantially ogee-shaped wings within said casing and adapted to admix the fuel and air 125 entering said casing, and means supported

by said wings for spreading the flame and directing the latter to impinge upon the inner wall of said extension.

5. A burner for gaseous fuel embodying therein a casing, an extension projecting from one end of said casing, and being provided with a series of orifices, air admission means connected to said orifices, a series of substantially ogee-shaped wings within said

10 casing and adapted to admix the fuel and

air entering said casing, and means supported by said wings for spreading the flame and directing the latter to impinge upon the inner wall of said extension.

In testimony whereof I have affixed my 15
signature in presence of two witnesses.

FREDERIC C. CHADBORN.
